W. J. WHITE

RAZOR BLADE HOLDER

Filed Feb. 17, 1926

INVENTOR.

William J. White.

BY
Carlos P. Griffin

ATTORNEY.

UNITED STATES PATENT OFFICE.

WILLIAM J. WHITE, OF SAN FRANCISCO, CALIFORNIA, ASSIGNOR OF ONE-HALF TO
WILLIAM H. GILBERT AND ONE-HALF TO VERRYL G. FOFT, BOTH OF SAN FRANCISCO,
CALIFORNIA.

RAZOR-BLADE HOLDER.

Application filed February 17, 1926. Serial No. 88,724.

This invention relates to a razor blade holder for the purpose of sharpening the blades, and while it is applicable to any of the ordinary thin blade type razors, it is especially intended for use with the double edged razors, one portion of the holder acting as a guard to prevent the blade from cutting the strap during the time one of the edges is being sharpened.

Another object of the invention is to provide means whereby the blade may be turned over in order to sharpen the second edge without removing the blade from the holder.

A further object of the invention is to provide a holder to which the blade is easily secured to or disconnected therefrom when it has been sharpened.

An embodiment of the invention is shown in the accompanying drawings in which the same reference numeral is applied to the same portion throughout the several figures of the drawings and of which there may be modifications.

Figure 1 is a side elevation of the blade and holder as it appears ready for use, showing the guard bar in the second position in dotted lines.

Figure 2 is a view in edge elevation of the blade and holder looking from the right of Figure 1.

Figure 3 is a view similar to Figure 2 with the blade removed therefrom, and with the spring for holding the blade disengaged from the holder.

Figure 4 is a view in edge elevation of the guard disengaged from the handle, and

Figure 5 is an end view of the guard disengaged from the handle.

The numeral 1 indicates a tubular handle which has a bar 2 extending therefrom at one end, said bar being bent over at 3 to engage and secure a spring 4 at one end. The spring 4 is curved so that it assumes the position shown in Figure 3 when not under stress. The handle portion of the spring indicated at 5 is narrow enough to pass into a slot 6 between the ends of two arms 7 and 8 which secure the guard bar 9 to the handle.

Two raised tabs 10 and 11 on the handle prevent the guard bar from passing beyond the end of the tubular portion of the handle. It will also be seen that the tubular portion of the handle has a slot 12 cut

therein which allows the reduced portion 5 of the spring 4 to pass thereto when the spring is depressed against the bar 2 by the thumb. Thereupon the guard is turned till the spring engages either of the notches 13 60 to 14 to prevent the guard from turning further.

Inside the arms 7 and 8 are the notches 13 and 14, the object of which is to provide means to stop the guard bar 9 with the spring 5 in either one of two positions to provide the protection for one edge of the blade necessary when sharpening the other edge of the blade either on a strap or on a hone. This blade guard is also made of such a width as to provide the proper angle for the sharpening of the blade secured in the holder, said blade being indicated at 15 in Figure 1.

As was previously mentioned, the holder 75 may be used in connection with the ordinary thin single edged blades with or without stiffener secured to one edge, or it may be used in conjunction with the common form of double edged safety razor blades, in which event it is only necessary to depress the spring and turn the guard 180 degrees to enable the user to sharpen the second edge.

In use the holder is drawn back and forth across the razor strap or hone precisely as an old style razor would be used to sharpen one edge of the blade, after which the guard is reversed in position and the second edge then sharpened.

Having thus described my invention, what I desire to secure by Letters Patent of the United States is as follows: but modifications may be made in carrying out the invention as shown in the drawings and in the above particularly described form thereof, within the purview of the annexed claims.

1. A razor blade holder comprising a tubular handle, a bar extending therefrom at one end, said bar being bent over at its end to form a clamp, a flat spring held in said clamp and adapted to curve outwardly from said bar in its free position, a slot in said handle to receive said spring, a sleeve on said handle, a slot in said sleeve, a guard bar on said sleeve and oppositely placed notches adapted to receive said spring on the inside of said sleeve at right angles to said guard bar.

2. A razor blade holder comprising a 110

tubular handle, a razor blade holding bar secured to the inside of said handle and extending therefrom, a spring clamp secured to the outer end of said bar and extending to the handle, said handle having a slot to receive the end of said spring, a rotatable sleeve on the handle having notches to engage the spring to lock the spring and sleeve in a given position on the handle, outwardly bent lugs on the handle to hold the sleeve in position, and a guard bar on the sleeve extending outwardly therefrom.

3. A razor blade holder comprising a

handle, a flat spring secured thereto adapted to hold a razor blade in a fixed position, a guard bar, a sleeve supporting said guard bar and surrounding said handle, said sleeve having a slot to permit the spring to pass into and out of the sleeve and also having notches whereby the spring is capable of stopping the sleeve in either of two positions to enable opposite edges of the blade to be sharpened.

In testimony whereof I have hereunto set my hand this 10 day of February A. D. 1926.

WILLIAM J. WHITE.
